United States Patent

Des. 238,754

Patented Feb. 10, 1976

238,754

BOTTLE

Carl E. Frahm and Shirley E. Frahm, both of 1428 Oak Meadow Road, Arcadia, Calif. 91106

Filed Aug. 5, 1974, Ser. No. 494,465

Term of patent 14 years

Int. Cl. D9—01

U.S. Cl. D9—86

FIG. 1 is a top plan view of a bottle showing our new design;

FIG. 2 is a side elevational view, the opposite side being the same in appearance as the side shown; and

FIG. 3 is a bottom plan view thereof.

We claim:

The ornamental design for a bottle, as shown and described.
